(74) *Attorney, Agent, or Firm*—Cislo & Thomas, LLP

(57) **CLAIM**

I claim the ornamental design for the dresser, as shown and described.

DESCRIPTION

FIG. 1 is a front elevational view of a dresser showing my new design;

FIG. 2 is right-side elevational view thereof;

FIG. 3 is left-side elevational view thereof;

FIG. 4 is a top plan view thereof;

FIG. 5 is an elevational detail of the center portion of the dresser illustrating the ornamentation thereon in enlarged detail; and,

FIG. 6 is an elevational detail shown separately for clarity of illustration showing one of the drawer pulls thereof in enlarged detail shown separately for clarity of illustration. The claimed design does not include any specific depth for the specific ornamental details shown within the perimeter moldings.

1 Claim, 6 Drawing Sheets
